170,003

COMBINED SERVICE AND DISPLAY COUNTER

Thomas Carvel, Chauncey, N. Y.

Application January 9, 1953, Serial No. 23,088

Term of patent 14 years

(Cl. D80—11)

To all whom it may concern:

Be it known that I, Thomas Carvel, a citizen of the United States, residing at Chauncey, in the county of Westchester and State of New York, have invented a new, original, and ornamental Design for a Combined Service and Display Counter, of which the following is a specification, reference being had to the accompanying drawing, forming part thereof.

Fig. 1 is a front perspective view of a combined service and display counter showing my new design; and

Fig. 2 is a rear perspective view of the same.

I claim:

The ornamental design for a combined service and display counter, substantially as shown.

THOMAS CARVEL.
